UNITED STATES PATENT OFFICE

144,713

DESIGN FOR AN AIRPLANE

Edward H. Heinemann and Leo J. Devlin, Los Angeles, Calif., assignors to Douglas Aircraft Company, Inc., Santa Monica, Calif.

Application November 25, 1941, Serial No. 104,328

Term of patent 7 years

(Cl. D71—1)

To all whom it may concern:

Be it known that we, Edward H. Heinemann and Leo J. Devlin, both citizens of the United States and residents of Los Angeles, in the county of Los Angeles and State of California, have invented a new, original, and ornamental Design for an Airplane, of which the following is a specification, reference being had to the accompanying drawings, forming a part thereof:

Figure 4 is a side elevational view of the subject airplane depicted in Figures 1, 2 and 3, with the landing gear thereof in the retracted position; and

We claim:

The ornamental design for an airplane, substantially as shown.

EDWARD H. HEINEMANN.
LEO J. DEVLIN.
